UNITED STATES PATENT OFFICE.

JAMES FIDDES AND JOHN FORDYCE WATT, OF ABERDEEN, SCOTLAND.

FIRE-EXTINGUISHING SYSTEM.

SPECIFICATION forming part of Letters Patent No. 787,505, dated April 18, 1905.

Application filed January 23, 1905. Serial No. 242,343.

To all whom it may concern:

Be it known that we, JAMES FIDDES and JOHN FORDYCE WATT, subjects of the King of the United Kingdom of Great Britain and 5 Ireland, and residents of Aberdeen, in the county of Aberdeen, Scotland, have invented certain new and useful Improvements in Fire-Extinguishing Systems, of which the following is a specification.

- 10 This invention relates to a fire-extinguishing system comprising water-sprinklers or like devices connected to a water or other fluid-discharge pipe, with means for maintaining said pipes dry or empty without compressing 15 air in said pipes and means for automatically admitting fluid to said pipes when the sprinklers are automatically opened on outbreak of fire. Under the invention the valve normally preventing access of water to the discharge- 20 pipes is maintained on its seat by the action on a diaphragm of air compressed within metal tubing, which may be led alongside the discharge-pipes, and on the outbreak of fire and the compressed air escaping the said valve 25 rises from its seat, so as to admit water to said pipes. By having the means for permitting escape of compressed air more sensitive than the automatic device for opening the 30 sprinkler-outlets the escape of compressed air and the admission of fluid to the discharge-pipes take place in advance of the opening of the sprinkler-outlet, so that immediately the 35 sprinkler is actuated the fluid has an unrestricted discharge. On the other hand, should either the means normally closing the 40 sprinkler-outlet or the means normally preventing escape of air be accidentally broken or removed there will be no discharge of water, which, indeed, can only take place when both

holds closed a valve interposed in the water-supply pipe, but allows said valve to rise off its seat at the time any sprinkler is actuated. 50

Referring to the drawings, to a water-main *d* are connected branch water-pipes *c*, provided with a series of discharge-boxes *b*. 55 Equidistant from the discharge-boxes are brackets *e*, adjustably mounted on the pipes *c*, and connected to said brackets is or are a stretched metal wire or wires *a*, supporting a slotted lever, which in turn embraces a glass 60 dome normally closing the sprinkler-outlet, as fully described in the specification of our co-pending application for patent, Serial No. 225,454.

Preferably alongside each pipe *c* and adjacent to the ceiling for each story is led a seamless brass or other metal tube *g* filled with compressed air. A metal junction-piece interposed in said tubing is provided with a tubular glass dome or bulb or other frangible 70 device normally preventing escape of air from said tubing, but automatically fractured on sudden rise of temperature upon the release of a slotted lever normally supported from a stretched wire by means of a pin entering a 75 recess in the weighted end of the lever, as fully described in the specification of our co-pending application Serial No. 242,344. The said air-tubes *g* are each connected to a common air-duct *k*, a back-pressure valve *l* being 80 fitted in the tube *g* for each floor of the building, so as to prevent escape of air from any tube in a part of the building not affected by fire. All the tubes are filled with compressed air by means of an air-pump *m* or the like. 85

Alongside the main air-duct *k* is a diaphragm device *n*. (Shown more particularly in Fig. 2.) To the lower side of the vessel containing the rubber diaphragm is led a branch tube *o*. The diaphragm is normally forced up by 90 the air-pressure and acts, through the lever *o* and the spindle *o*², to press down on its seat a valve *o*³ in the water-main *d*. A stop-valve *p*, operated by hand, is likewise provided, so as to completely cut off the supply of water 95 to the pipes *c* after a fire is extinguished, but before the spindle *o*² is again depressed. A water-gage *q* is also provided, and the air-

In the accompanying drawings, which illustrate the invention, Figure 1 is a part-sectional elevation showing more or less diagrammatically an automatic fire-extinguishing system fitted in rooms on different floors. Fig. 2 is a sectional elevation, to enlarged scale, showing the diaphragm apparatus that normally

pressure is regulated, through the medium of the diaphragm apparatus, to press down on its seat the stop-valve in the junction-piece σ^3 against the upward pressure of the water, 5 and thus keep the pipes c dry or empty without compressing air in said pipes.

Connected to an extension of the tube σ is an air-pressure gage r , the pointer of which gage may be arranged, on its being turned 10 owing to undue fall of pressure on account of leakage, to close an electrical circuit and ring an alarm-bell r' .

Each of the air-tubes g extends from the main duct k to a combined pressure-gage and 15 signal device fully described in our copending application Serial No. 242,344.

On outbreak of fire, the pin supporting the sprinkler-lever being longer than the pin supporting the lever that fractures the device normally stopping escape of air, said last-named lever is under the same conditions released 20 in advance of the first-named lever. Consequently, the device for opening the outlet from the air-tubing being more sensitive than the devices for opening the sprinkler outlet or outlets, the compressed air in 25 the air-tubing will first escape, and on reduction of pressure in the tubing and the diaphragm yielding water will be admitted to the pipes c , and when the expansion of 30 the wire a automatically effects the opening of the sprinkler-outlet the water will instantaneously discharge from the sprinklers. On the other hand, should either the frangible 35 device closing a sprinkler-outlet or the dome or the like closing the outlet from an air-tube be accidentally broken there will be no discharge of water.

While the invention has been described more 40 especially with reference to the improvements set forth in our copending applications Serial Nos. 225,454 and 242,344, it is to be understood that the invention is not limited to the specific constructions therein shown, but the 45 pneumatic system may be adapted to existing sprinkler apparatus and the sprinkler apparatus may be adopted, in connection with other means, for maintaining the water-pipes normally dry or empty, as will be understood.

50 Having now described our invention, what we claim, and desire to secure by Letters Patent of the United States, is—

1. In automatic fire-extinguishing apparatus, in combination, a water-pipe, a sprinkler, 55 normally inactive, fitted on said pipe, automatically-acting devices for rendering said sprinkler active, air-tubing filled with compressed air, a frangible outlet in said tubing, a stretched wire, means adapted on expansion 60 of said wire to destroy said connection, a valve normally preventing passage of water into said pipe, and means actuated on escape of air from said tubing to open said valve, substantially as described.

2. In automatic fire-extinguishing apparatus, in combination, a water-pipe, a sprinkler, normally inactive, fitted on said pipe, automatically-acting devices for rendering said sprinkler active, air-tubing filled with compressed air, a frangible outlet in said tubing, 65 a stretched wire, a weight supported from said wire and released on expansion of said wire to fracture said frangible outlet, a valve normally preventing passage of water to said pipe and means actuated on escape of air from said 70 tubing, to open said valve, substantially as described.

3. In automatic fire-extinguishing apparatus, in combination, a water branch pipe, a 80 sprinkler, normally inactive, fitted on said pipe, automatically-acting devices for rendering said sprinkler active, air-tubing filled with compressed air, a frangible outlet in said tubing, a stretched wire, means adapted on expansion of said wire to fracture said frangible outlet, a valve normally preventing passage of water to said pipe, devices actuated on escape of air to open said valve, and an alarm actuated on reduction of air-pressure 85 in said tubing, substantially as described. 90

4. In automatic fire-extinguishing apparatus, in combination, a water branch pipe, a sprinkler normally inactive fitted on said pipe, automatically-acting devices for rendering said sprinkler active, air-tubing filled with 95 compressed air, a frangible outlet in said air-tubing, automatic means, more sensitive than said sprinkler-actuating means, adapted on abnormal rise of temperature to fracture said frangible outlet to permit escape of air from 100 said tubing, a valve adapted to prevent passage of water into said pipe, and diaphragm apparatus connected to said tubing, normally holding said valve closed and adapted on reduction of air-pressure in said tubing to permit said valve to rise off its seat to admit water to the sprinklers, substantially as described. 105

5. In automatic fire-extinguishing apparatus, in combination, a water branch pipe, a 110 sprinkler normally inactive fitted on said pipe, automatically-acting devices for rendering said sprinkler active, air-tubing filled with compressed air, a frangible outlet in said tubing, a stretched wire, a weighted lever, a 115 catch supporting said lever from said wire and adapted on expansion of said wire to release said lever to fracture said frangible outlet, a valve normally preventing passage of water to said pipe, and diaphragm apparatus 120 actuated on escape of air from said tubing to open said valve.

6. In automatic fire-extinguishing apparatus, in combination, a water-pipe, a sprinkler connected to said water-pipe, a frangible outlet, means normally maintaining said water-pipe dry without compressing air in said pipe, 125 automatically-acting devices for fracturing

said frangible outlet so as to open said sprinkler, and automatic devices more sensitive than said first-mentioned devices and adapted on sudden rise of temperature to effect admission 5 of water to said pipe.

7. In automatic fire-extinguishing apparatus, in combination, a water-pipe, a valve, means normally maintaining said valve in position to prevent passage of water to said 10 pipe, a sprinkler fitted on said water-pipe, frangible means normally closing the sprinkler-orifice, automatically-acting devices for fracturing the orifice-closing means, and automatic devices more sensitive than said first- 15 mentioned devices and adapted on sudden rise of temperature to permit said valve to rise off its seat to admit water to said sprinkler.

8. In automatic fire-extinguishing apparatus, in combination, a water branch pipe normally kept dry without compressing air in said pipe, sprinkler devices normally inactive fitted on said pipe, automatic means adapted on sudden rise of temperature to render said 20 sprinklers active, air-tubing filled with compressed air, a frangible outlet in said air-tubing, automatic means, more sensitive than said sprinkler-actuating means, adapted on abnormal rise of temperature to fracture said outlet to permit escape of air from said tubing, a valve adapted to prevent passage of water to said pipe, diaphragm apparatus connected to said tubing, normally holding said valve closed, and adapted, on reduction of air-pressure in said tubing, to permit said 25 valve to open to admit water to the sprinklers, and an alarm operated on reduction of air-pressure in the tubing.

9. In automatic fire-extinguishing apparatus, in combination, a water branch pipe normally kept dry without compressing air in said pipe, sprinkler devices, normally inactive, fitted on said pipe, a stretched wire adapted on expansion to render said sprinklers active, air-tubing filled with compressed air, a frangible outlet in said air-tubing, a second stretched wire, means operated on expansion of said second wire to fracture said frangible outlet to permit escape of air from said tubing, a valve adapted to prevent passage of water to 45 said water-pipe, and diaphragm apparatus connected to said tubing, normally holding said valve closed, and adapted on reduction of air- 50

pressure in the tubing to permit said valve to rise off its seat to admit water to said water-pipe.

55

10. In automatic fire-extinguishing apparatus, in combination, a water branch pipe normally kept dry without compressing air in said pipe, said pipe having a discharge-orifice, a fragile dome normally closing the orifice, a stretched wire, a weighted lever, means normally supporting said lever from said wire but adapted on undue expansion of said wire to release said lever to break said dome, an air-tube filled with compressed air, a frangible 60 outlet in said tube, a second stretched wire, a second weighted lever, means normally supporting said second lever from said second wire and adapted on dilation of said second wire to release said second lever to break said 65 frangible outlet, a valve adapted to prevent passage of water to said branch pipe, and diaphragm apparatus normally holding said valve closed, but adapted, on reduction of air-pressure in said tubing to permit said valve to rise 70 off its seat to admit water to said branch pipe.

11. In automatic fire-extinguishing apparatus, in combination, water branch pipes normally kept dry without compressing air in said pipes, sprinkler devices normally inactive 80 fitted on said pipes, stretched wires, devices adapted on expansion of said wires to render said sprinklers active, an air-duct, branch air-tubes, back-pressure valves connected to said air-tubes, an air-pump for filling said air-duct 85 and branch tubes with compressed air, frangible outlets in said air-tubes, stretched wires, means more sensitive than said sprinkler-actuating means adapted on dilation of said last-named wires to break said frangible outlets, a 90 valve adapted to prevent access of water to said pipes, and diaphragm apparatus normally holding said valve closed but on escape of air permitting said valve to open to admit water to said pipes.

In testimony whereof we have signed our names to this specification in the presence of two subscribing witnesses.
